UNITED STATES PATENT OFFICE.

CHARLES A. ANDERSON, OF OAKLAND, CALIFORNIA.

APPARATUS FOR EXHAUSTING WELLS.

Application filed November 25, 1925. Serial No. 71,290.

This invention relates to apparatuses for lifting fluids from deep wells by air pressure.

It is the principal object of the present invention to generally improve and simplify apparatuses of the character referred to whereby to provide a simple and inexpensive apparatus for exhausting liquid from deep wells by the use of air under pressure, which 10 apparatus will operate to automatically discharge a predetermined quantity of air under pressure into the well at intervals to lift the liquid therein.

In carrying out this object I provide an air 15 induction pipe which extends downwardly into the well. The lower end of this pipe is fitted with a discharge nozzle. The upper end of the induction pipe is connected with an air reservoir to which air under pressure 20 may be delivered from an air compressor. An automatic control valve controls the discharge of air from the tank to the induction pipe. This valve operates automatically to admit air from the air tank to the induction 25 pipe when the air pressure in the tank reaches the maximum working pressure. The valve automatically closes to interrupt the communication between the tank and the induction pipe when the pressure in the tank drops 30 below the minimum working pressure which is considerably less than the maximum working pressure.

One form which the invention may assume is exemplified in the following description 35 and illustrated by way of example in the accompanying drawings, in which:

Fig. 1 is a view of the apparatus with parts in section to more fully disclose the construction thereof.

Fig. 2 is an enlarged view of the main 40 valve showing the manner in which it is operated.

Referring more particularly to the accompanying drawings, 10 indicates a well having a casing 11. The top of this casing is fitted with an elbow 12 which connects with an eduction pipe 14. Extending downwardly through the elbow 12 is an air induction pipe 15, the lower end of which extends considerably below the fluid level in the casing. The lower end of the air induction pipe 15 is fitted with an air discharge nozzle 16 which is in the shape of an inverted cone. This nozzle is formed with a plurality of upwardly projecting discharge ports 17 arranged in

spaced relation around the upper face of the nozzle and exteriorly of the pipe 15 with the interior of which they communicate.

It is manifest from the foregoing that air under pressure delivered to the pipe 15 will discharge upwardly through the ports 17 below the fluid level in the well. This air by natural expansion and pressure will lift the fluid in the casing and discharge it through the eduction pipe 14.

In the present instance I have provided means for intermittently discharging air under pressure within the well through the pipe 15. This permits the well to fill up after each operation and also renders the use of 65 large capacity air pumps and accompanying equipment unnecessary.

To accomplish this I provide a storage tank 18 to which air under pressure may be delivered by a small air compressor of any 70 standard design (diagrammatically illustrated in the drawing). The pipe line between the compressor and tank 18 is fitted with a safety valve 19 which is adapted to open after a predetermined pressure has been 75 built up in the tank. For example, it will be assumed that the maximum working pressure is 250 pounds and that the safety valve will open at 260 pounds to prevent any excessive pressure to be built up in the tank.

The tank 18 is also fitted with a discharge pipe 20 which connects with a T fitting 21. One leg of this fitting is connected with a discharge pipe 21^a and the other leg with an automatic control valve 22. This valve is 80 controlled by a spring 23 which will permit the valve to open when the pressure in the tank equals the working pressure. When 85 this valve is opened air under pressure will pass through the valve and into a pipe 24 which communicates with the operating cylinder 25 of a main cut-off valve 26. This operating cylinder 25 is fitted with a spring pressed plunger 27 which will rise when a predetermined pressure is built up in the pipe 24. 90 The pressure required to elevate the plunger 27 being the minimum working pressure which in the present instance is 100 pounds. That is, the plunger 27 will remain elevated 95 as long as a pressure of 100 pounds is exerted thereon. The plunger 27 is connected by a link 28 to the operating arm 29 of the main cut-off valve 26 which controls the passage of air through the discharge pipe 21 which connects the tank 18 with the eduction pipe 14.

This connection is such that when the plunger 27 rises the valve 26 will open and when the plunger lowers the valve 26 will close.

The cylinder 25 also connects with the induction pipe 15. A check valve 31 is interposed between the pipe 15 and the cylinder 25 so that pressure passing into the cylinder 25 through the pipe 24 will not pass into the pipe 14. However, when the main valve 26 is opened the pressure in the pipe 14 will open and place the cylinder 25 into communication with the pipe 15.

Therefore, as long as the pressure in the pipe 15 is above 100 pounds the plunger 27 will remain raised and maintain the main valve 26 open but when the pressure in the pipe 15 goes below 100 pounds the plunger 27 will lower and close the valve 26 to interrupt the communication between the tank 18 and the pipe 15.

Due to the provision of the control valve 22, the main valve 26 will not be opened until the pressure in the tank reaches the maximum working pressure which is 250 pounds. However, when the valve 26 is once opened it will not be closed until the pressure in the tank drops below the minimum working pressure of 100 pounds which is required to maintain the plunger 27 elevated in the cylinder 25.

The operation of the apparatus is as follows: The air compressor is operated to deliver compressed air to the tank 18, it being assumed that the valves 22 and 26 are closed. The air compressor will continue to deliver air to the tank 18 until the pressure therein reaches the maximum of working pressure of 250 pounds. At this point the valve 22 will open and admit air through the pipe 24 to the cylinder 25. This air under pressure will raise the plunger 27 and through the medium of the link 28 and the arm 29 will open the main valve 26.

The air under pressure in the tank 18 will then discharge through the discharge pipes 20 and 21^a to the induction pipe 15. The air will discharge through the ports 17 in the nozzle 16 at the lower end of the pipe 15 and through natural expansion and pressure will elevate the liquid in the well and discharge it through the eduction pipe 14.

As soon as the pressure in the tank 18 becomes below the maximum working pressure of 250 pounds, the valve 22 will close. This, however, will not effect the plunger 27 as communication will be established from the induction pipe 15 through the check valve 31 to the cylinder 25 and act against the plunger 27. As this plunger will remain elevated as long as a pressure of 100 pounds is exerted thereagainst the main valve 26 will be maintained open until the pressure in the tank drops below the minimum working pressure of 100 pounds.

When this low pressure has been reached

the plunger 27 will lower and close the valve 26, thereby entirely disconnecting the air tank 18 from the induction pipe 15.

Communication will be automatically re-established between the tank 18 and the induction pipe 15 as soon as the air compressor builds up the pressure in the tank 18 to the maximum working pressure of 250 pounds. At this point the operation will be just as described until the pressure in the tank drops below the minimum working pressure. The communication between the tank 18 and the pipe 15 will then again be automatically interrupted as described.

It is intended that the quantity of air discharged at each operation be sufficient to elevate all the liquid in the well above the nozzle 16 at the lower end of the pipe 15. Therefore, during the interruption in the operation of the apparatuses the well will have opportunity to fill up again to the normal level therein.

By constructing the apparatus according to my invention a very inexpensive device can be built to raise liquid from considerable depths. Also the device will be comparatively inexpensive to construct due to the fact that a very simple air compressing apparatus may be employed.

The present apparatus is capable of use in connection with deep oil wells and also may be used for elevating water from deep wells in dry arid lands. It would be particularly applicable for use in desert countries where water must be lifted from great depths. In the latter use a windmill may be provided for operating the air compressor. This would provide very economical means for elevating water from wells.

While I have shown the preferred form of my invention, it is to be understood that various changes may be made in its construction without departing from the spirit of the invention as defined in the appended claims.

Having thus described my invention, what I claim and desire to secure by Letters Patent is:

1. An apparatus for lifting liquid from deep wells comprising an eduction pipe extending downwardly into said well below the fluid level therein, an air induction pipe extending downwardly within said eduction pipe to a point below the liquid level in the well, an air tank operatively connected to said induction pipe, a valve controlling the passage of air from the tank to said induction pipe, an air compressor adapted to constantly operate to build up pressure in said tank to a maximum working pressure, means whereby said valve will be automatically opened when the pressure in said tank reaches the maximum working pressure, and means for automatically closing said valve when the pressure in said tank drops below a minimum

working pressure which is considerably less than the maximum working pressure.

2. An apparatus for elevating liquids from deep wells comprising an eduction pipe extending downwardly into said well below the level therein, an air induction pipe extending downwardly through the eduction pipe to a point below the liquid level, a discharge nozzle at the lower end of said induction pipe, said nozzle having upwardly directed discharge ports arranged in a circle exteriorly of the induction pipe, an air storage tank, a connection between the storage tank and the induction pipe, a main valve controlling said connection, means constantly delivering air under pressure to said tank and adapted to build the pressure therein up to a maximum working pressure, operating means controlling said main valve, means whereby said operating means will be automatically actuated to open said main valve when the pressure in said tank reaches the maximum working pressure, said operating means being adapted to automatically close said valve when the pressure in said tank drops below a minimum working pressure which is considerably less than the maximum working pressure.

3. An apparatus for lifting liquid from deep wells comprising an eduction pipe extending downwardly into the well below the liquid level therein, an air induction pipe extending downwardly within the eduction

pipe to a point below the liquid level in the well, a discharge nozzle at the lower end of said air induction pipe, a tank adapted to contain air under pressure, an air compressor adapted to constantly operate to build up air pressure in said tank, a connection between said tank and said air induction pipe, a main valve controlling said connection, an operating cylinder, a plunger in said cylinder, an operative connection between said plunger and said main valve whereby when said plunger is moved in one direction said valve will be opened, and when moved in the other direction said valve will be closed, a connection between said tank and said cylinder whereby pressure from the tank may be admitted to said cylinder to move the plunger in a direction to open the main valve, a valve controlling said connection and adapted to automatically open when the pressure in said tank reaches the maximum working pressure, the opening of said valve admitting pressure from the tank to the cylinder to actuate the plunger to open the main valve, said plunger being adapted to maintain the valve open until the pressure in the tank drops below the minimum working pressure considerably less than the maximum working pressure, and a spring actuating the plunger to close the main valve when the pressure in the tank drops below the minimum working pressure.

CHARLES A. ANDERSON.
